PHONOGRAPH MOTOR CONTROL

Alfred F. Welch, Fort Wayne, Ind., assignor to
General Electric Company, a corporation of
New York

Application September 4, 1937, Serial No. 162,500

17 Claims. (Cl. 274—1)

My invention relates to the control of electrically driven phonographs and its object is to provide for control of the motor by the ordinary movements of the tone arm.

In connection with electrically driven phonographs I have found that it is desirable to apply a higher voltage to the motor at the time of starting than when playing the record. Where automatic record changing mechanisms are used it is also desirable to apply a higher voltage to the motor during the record changing operation than when playing a record. The starting and record changing operations require a higher available motor torque than is necessary or desirable during the playing of the record, because generally speaking, if a phonograph motor of the usual alternating current synchronous type is energized to obtain maximum torque output its operation is usually accompanied by an audible electromagnetic hum which is undesirable during playing of the record. According to my invention I provide a driving motor of sufficient torque capacity to start the phonograph into operation promptly and to perform automatic record changing operations and energize the motor for high-torque output during such operations. During the record playing period I materially reduce the voltage applied to the motor to a point where its torque is only amply sufficient for this operation and thus obtain unusually quiet operation. This control of the motor is accomplished by the movement of the tone arm of the phonograph so that the necessary switching operations are performed automatically by reason of the normal operation of the phonograph. I prefer to combine with the above mentioned motor torque control means for automatically cutting off the motor after a record has been played and when the tone arm is moved to a particular non-playing position of rest.

The features of my invention which are believed to be novel and patentable will be pointed out in the claims appended hereto. For a better understanding of my invention reference is made in the following description to the accompanying drawing which illustrates in Fig. 1 a partial plan view of a phonograph record with a tone arm of a phonograph in playing position; Fig. 2 illustrates a side view of electrically driven phonograph apparatus with the tone arm and the motor control mechanism partially in section and with the tone arm in playing position and the motor energized at reduced voltage; Fig. 3 shows the motor switching device when the motor is de-energized; Fig. 4 shows the motor switching de-

vice when the motor is fully energized; Fig. 6 is an enlarged sectional view of a portion of the control mechanism shown in Fig. 2; Fig. 5 is a plan view of a ratchet mechanism shown in section in Fig. 6 which is used to open the motor circuit when a record has been played, the parts being shown in the position they will assume when the tone arm is approaching the center of the record, and Fig. 7 is another plan view of this ratchet mechanism with its parts in the position they will assume when the tone arm is swung to one side of the record.

Figs. 1 and 2 show parts of an electrically driven phonograph to which my invention is applied. The record disc is indicated at 10 on the turn table 11, pivoted at the axis 12 and driven by a self-starting electric motor 13 which is located beneath the top wall 14 of the phonograph cabinet. The tone arm of the phonograph is shown at 15. The tone arm is pivoted on a horizontal axis 16 to a support 17 in order that the tone arm may be raised and lowered, and the support 17 is secured to a vertical shaft 18 which is pivoted in a bushing bearing 19 secured in the top wall of the cabinet. Thus the tone arm may pivot with shaft 18 to swing over the record in a horizontal plane and may be raised and lowered by movement about pivot 16, and thus has the usual freedom of movement. In Fig. 2 the center line of the tone arm is marked "Run" and this is the horizontal position of elevation which the tone arm assumes when its needle 20 is resting on the record 10 in playing position. When the tone arm is lifted from the record its center line will fall along the line marked "Start" in Fig. 2 and when the tone arm is swung to one side of the turn table and is lowered to a position of rest on a rubber button 21 the center line thereof will fall along the line marked "Off". The arrangement as thus far described is a usual arrangement.

The vertical shaft 18 of the tone arm support is made hollow and within this hollow shaft is a switch operating rod 21. The upper end of this rod has an elongated eye 22 therein through which passes a horizontal pin 23 secured to the tone arm 15. The pin 23 passes through the vertical axis of rotation of the tone arm and thus freely passes through the eye 22 in any rotative position of the tone arm. The lower end of the rod 21 carries an insulated switch operating button 24 which is preferably screwed on the rod 21 with a tight fit so that it may be raised and lowered slightly with respect to rod 21 for adjustment purposes. The button 24 normally rests on a resilient switch contact member 25.

The contact member 25 has sufficient resilient strength within its range of movement to raise rod 21 unless this is prevented as by reason of the lower limit of the eye opening 22 coming against pin 23.

Switch contact member 25 cooperates with two additional contact members 26 and 27 and these contact members comprise the control switch for the motor 13. The contact members are supported near one end in an insulating support 28 secured to the under side of the cabinet cover 14. The upper contact member 27 is connected directly to one motor terminal 29. The central contact member 26 is connected to motor terminal 29 through a suitable current reducing resistance 30. The lower contact member 25 is connected to one side of a supply source 31 and the other side of this source is connected to the other terminal of the motor. The free ends of the contact arms are provided with cooperating contacts as shown, and the selective opening and closing of these contacts is controlled by the vertical position of the tone acting arm through rod 21, button 24 and the lower resilient contact arms 25 and 26.

When the tone arm is raised to the position indicated "start" in Fig. 2 the contacts of arms 25, 26 and 27 are closed on each other as shown in Fig. 4. This connects the motor 13 directly to the source of supply 31. This places full voltage on the motor and it starts quickly and operates at full power capacity so long as this switching condition exists.

When the tone arm is lowered to playing position with its needle 20 on the record disc 10, position "run" Fig. 2, contact member 25 is partially depressed and this permits resilient contact member 26 to move downward sufficiently to open its upper contact with contact member 27 as shown in Fig. 2. This inserts resistance 30 in the motor circuit to lower the motor voltage and allows it to run with minimum magnetic hum during the time the record is being played.

When the tone arm is lowered to the position "off", Fig. 2, and rests on button 9 in the idle position, which is lower than the playing position, the contact member 25 is further depressed to open its contact with member 26 as shown in Fig. 3. It is evident that the tone arm must be swung to the side of the turn table in order to be lowered to this "off" position. It is thus seen that using the invention as thus far described the phonograph may be operated by a child or any other person merely by the usual manual movement of the tone arm from a position of rest to any playing position and vice versa, and without consciously performing any switching or manual starting or stopping operation. The switching mechanism is entirely within the cabinet, which is desirable for protection to such mechanism and from the point of view of avoiding electric shocks, particularly to children.

Applying a higher voltage to the motor at start than when playing the record is desirable for several reasons. The reduction in noise during playing of the record has been mentioned and is important. Quick starting is desirable because by the time the operator lifts the tone arm from button 9 and rests it on the record with the needle in the outer groove in the normal manner, the record is up to proper speed and the dreary sound which is sometimes heard when a phonograph record is played on a rising speed is not experienced. The invention makes

it possible to obtain satisfactory operation with some saving in electricity as compared to that which would be used with a constant voltage phonograph motor drive system. Some reduction in motor size is permissible since it will be evident that the torque required of the motor during the actual playing period is small as compared to that required for quick starting. With my invention it is permissible to use a relatively small motor and momentarily over-energize it to obtain high power for starting since the starting period is very short and starting operations are time spaced sufficiently that heating of the motor due to such momentary and relatively infrequent starting is not a troublesome factor. The voltage control of the motor as hereinbefore described is suitable for and desirable with automatic record changing phonographs. I have not shown such automatic changing features and this is unnecessary to support the truth of this statement, since it will be observed that whether a record is changed manually or automatically the tone arm must be raised and when the tone arm is raised, the power capacity of the motor drive is increased by the control described. This increased power capacity is thus available to start the motor or to perform any other extra duty that should be or is performed when the tone arm is in a raised position.

In the ordinary phonograph not equipped with record changing apparatus it is desirable that when the apparatus has finished playing a record it will shut itself down automatically and a mechanism for performing this operation will now be described. Phonograph records may be made and many of them as now made have an inner eccentric groove 32 (see Fig. 1) into which the needle 20 of the phonograph arm is guided when the playing of the record is completed. If the motor continues to run, the eccentric groove gives the tone arm a back and forth rotary motion about its vertical pivot point. I make use of the horizontal movement of the tone arm over the final range of its movement to this record ending position where the needle is in groove 32 and, if necessary, the back and forth motion of the tone arm as the needle rides in the eccentric groove 32 for operating a ratchet device best shown in Figs. 5 and 7 for moving switch rod 21 downward to open the circuit of the driving motor 13 at contacts 25 and 26 notwithstanding the fact that the tone arm remains at playing elevation.

Secured in fixed relation to the bottom of hollow shaft 18, I have provided a short arm 33 on the outer end of which and on its upper side is pivoted a ratchet pawl 34. Any rotary motion of the tone arm 15 is conveyed to ratchet pawl arm 33 and hence the ratchet pawl 34 has a back and forth ratcheting motion when the needle of the tone arm rides in eccentric groove 32. This ratchet pawl 34 is biased against the periphery of a ratchet wheel 35 by a light spring 36. The ratchet wheel is free to turn and has a bearing on hollow shaft 18. The ratchet wheel is normally biased to the rotary position shown in Fig. 7 by a spring 37 secured between a stationary post 38 and an off-center pin 39 protruding from the upper side of such ratchet wheel.

In the rotary position of ratchet wheel 35 shown in Fig. 7 it is preferably prevented from further rotation in a counter-clockwise direction by a stop pin 40 against which a shoulder 41 of the ratchet wheel is urged by spring 37.

A check pawl 42 is provided. This pawl is pivoted on a post 43 and the pawl is urged against ratchet wheel 35 by a spring 44. The check pawl 42 carries an elongated finger 45 which serves to remove both the advancing pawl 34 and the check pawl 42 from the ratchet wheel when the tone arm is swung counter-clockwise to a record beginning position where its needle end is opposite the outer record groove or beyond 10 to one side of the record such as the position designated by line 15a, Fig. 7. This result is accomplished by reason of the rear end of pawl 34 striking the inner surface of finger 45. Both pawls are turned counter-clockwise on their pivot 15 points and their pawl ends are retracted from the ratchet wheel. As soon, however, as the tone arm approaches the end of playing range and reaches some such position as 15b, Fig. 5, which is about the position of the tone arm shown in 20 Fig. 1, finger 45 releases pawl 34 and both pawls return to ratcheting position against ratchet wheel 35. The posts 38, 40 and 43 may extend downward from the top of the cabinet as shown for post 43, Fig. 2.

25 It will now be evident that when the tone arm reaches some such playing position as shown in Fig. 1, ratchet wheel 35 will be caught by pawl 34 and will then turn in a clockwise direction moving shoulder 41 away from stop pin 40 until the 30 playing of the record is completed and the tone arm moves to the record ending groove 32 and then, if necessary, as the tone arm takes up the wobbling or back and forth rotary motion, pawl 42 will hold the ratchet wheel from returning 35 as pawl 34 backs up and advances and ratchets the wheel 35 further in a clockwise direction against the restraining action of spring 37. The teeth of the ratchet wheel should be spaced not greater than the throw of ratchet pawl 34 when 40 the tone arm takes up the wobbling motion.

Projecting from the under side of ratchet wheel 35 is a button 46 which acts with a cam sector 47 secured to switch actuating post 21 to move this post downward as ratchet wheel 35 is 45 advanced in a clockwise direction. Downward movement of post 21 is permitted independently of the tone arm by reason of the lost motion connection consisting of the elongated eye 22 in the top of post 21 where it is hooked to the tone arm by the pin 23. The post 21 and cam sector 47 are prevented from rotating with respect to the tone arm by pin 23.

The parts are so adjusted that as the needle moves the tone arm from the final music playing 55 groove to the groove 32 or shortly after the tone arm needle reaches the eccentric groove 32 and gives the tone arm a few back and forth ratcheting movements upon the completion of the playing of a record, cam button 46 will have advanced far enough on the rising surface of cam sector 47 to move post 21 down sufficiently to open switch 25, 26 as shown in Fig. 3. Hence, the motor is stopped automatically as or shortly after a record is completed if the apparatus is left unattended. This performs the same switching result as is accomplished by lowering the tone arm and of course it is unnecessary to allow the apparatus to cut off automatically if an attendant 60 is present and raises the tone arm and returns it to "off" position before the automatic cut-off has an opportunity to complete its action. Whether the automatic cut-off device has completed its action or otherwise, such automatic 70 device is returned to its initial or inactive con-

dition as shown in Fig. 7 as soon as the tone arm is moved to position 15a.

The cam sector 47 is in the shape of an L and is resilient so that the tone arm may be raised and with it post 21 even though the cam button 5 46 is on the high part of cam sector 47 and is urging the post 21 downward. The fact that cam sector 47 has some resiliency does not prevent it from moving post 21 downward against the tension of switch contact finger 25 in an automatic shut-off operation because at this time the only force opposing such downward movement is the relatively light upward tension of spring contact finger 25.

When the tone arm is raised from near the center of the record and while raised during its movement to "off" position, it will be evident that the motor will be momentarily fully energized. This does no harm and in fact if the same record is to be replayed it is desirable, as then the record will be up to speed as the tone arm is lowered into playing position. It is contemplated that a synchronous driving motor will be used so that its full operating speed will be correct regardless of the voltage applied thereto. The entire starting, stopping and torque control mechanism is inclosed and protected. There are no switches or other starting or stopping gadgets exposed.

In accordance with the provisions of the patent statutes, I have described the principle of 30 operation of my invention together with the apparatus which I now consider to represent the best embodiment thereof but I desire to have it understood that the apparatus shown is only illustrative and that the invention may be carried out by other means.

What I claim as new and desire to secure by Letters Patent in the United States is:

1. In a phonograph, a turn table, an electric motor for driving said turn table, a tone arm pivoted for movement about a horizontal axis such that the tone arm may be raised above and lowered to a playing position, an energizing circuit for said motor, voltage changing means for said motor associated with said circuit, and means 40 associated with the tone arm and operated by such raising and lowering movement of said tone arm for controlling said voltage changing means to respectively increase and decrease the voltage applied to said motor.

2. In a phonograph, a turn table, an electric motor for driving said turn table, a tone arm pivoted so as to be raised above and lowered below a playing position with respect to said turn table, an energizing circuit for said motor including circuit opening means and voltage changing means, and means operated by said tone arm for opening and closing said circuit as the tone arm is lowered below and raised to playing position respectively, and for increasing and decreasing 55 the voltage applied to said motor as the tone arm is raised above and lowered to its playing position respectively.

3. In a phonograph, a turn table, an electric motor for driving said turn table, a tone arm 65 pivoted so as to be raised above and lowered below a playing position with respect to said turn table, an energizing circuit for said motor, a voltage reducing resistance, switching means for opening and closing said circuit and cutting said resistance 70 in and out of said circuit, and means operated by the raising and lowering movements of said tone arm for operating said switching means such that when the tone arm is below playing position the motor circuit is open, when the tone arm is in 75

playing position the circuit is closed through said resistance and when the tone arm is raised above playing position the circuit is closed independently of said resistance.

5. In a phonograph, a turn table, an electric driving motor for said phonograph, a tone arm pivoted so as to be raised above and lowered to a playing position with respect to said turn table, a hollow vertical shaft to one side of said turn table pivoting said tone arm about a vertical axis, an energizing circuit for said motor, control means therefor, and means secured to said tone arm and passing through said hollow shaft for operating said circuit control means in response to the 10 raising and lowering movement of said tone arm.

5. In a phonograph, a turn table, an electric driving motor therefor, a tone arm pivoted for movement about a vertical axis to one side of said turn table so as to be swung to and from a playing 15 position over said turn table, and pivoted about a horizontal axis so as to be raised above and lowered to a playing position with respect to said turn table, an energizing circuit for said motor, circuit control means therein, and an operating member 20 for said control means connected to said tone arm so as to be operated by the raising and lowering movements thereof when the tone arm is in any rotative position about its vertical axis of rotation.

30. 6. In a phonograph, a record supporting turn table, a tone arm pivoted to swing in a horizontal plane over said turn table between record beginning and record ending positions and also pivoted for vertical movement above and below a record 35 playing position with respect to said turn table, an electric motor for driving said turn table, a switch for said motor, means operated by the raising of said tone arm to playing position for closing said switch and means operated by the horizontal movement of said tone arm to record 40 ending position for opening said switch while the tone arm remains in a vertical playing position.

7. In a phonograph, a record supporting turn table, a tone arm pivoted to swing over said turn table in a horizontal plane, inclusive of a record 45 playing range, from an outer record beginning position to an inner record ending position, and pivoted for vertical movement above and below record playing positions, and having a position of rest outside the record playing range and below record playing position, an electric motor for driving said turn table, a switch for said motor, means operated by the raising of said tone arm from said position of rest to playing position for closing said 50 switch to start the motor and means operated by inward horizontal movement of said tone arm for opening said switch after moving through the record playing range.

8. A phonograph, comprising a record supporting turn table, a tone arm pivoted to swing over said turn table in a horizontal plane from an outer position to one side of said turn table, inwardly through a record beginning position and through a record playing range to an inner record 55 ending position, and also pivoted for vertical movement from below record playing position to above record playing position, said tone arm having a position of rest to one side of the turn table and below vertical playing position, an electric motor for driving said turn table, a switch for starting and stopping said motor, and means operated by the movements of said tone arm for closing and opening said switch, said means being so correlated with the switch and tone arm that the 60 switch is open when the tone arm is in said position.

tion of rest, is closed by vertical movement of the tone arm from such position of rest to playing position, and is opened by inward horizontal movement of said tone arm to record ending position after moving through its record playing range when said tone arm is in a vertical playing position.

9. In a phonograph, a record supporting turn table, an electric motor for driving said turn table, switching means biased to closed condition 10 for starting and stopping said motor, a tone arm pivoted for horizontal movement over said turn table from an outer record beginning position to an inner record ending position, ratchet means operated by the inward movement of said tone 15 arm as it approaches record ending position during a record playing operation for opening said switch, said ratcheting means being rendered ineffective by outward movement of the tone arm from record ending to record beginning position 20 whereby the switch is permitted to close.

10. In a phonograph, a record supporting turn table, a grooved phonograph record thereon, a tone arm pivoted for movement in a horizontal plane, a needle on said tone arm adapted to rest 25 upon the record to guide the tone arm over the record in a record playing operation, an electric motor for driving said record, a switch for said motor and means responsive to the horizontal movement of said tone arm in a record 30 playing direction for opening said switch and responsive to movement in the opposite direction for closing said switch.

11. In a phonograph, an electric driving motor therefor, a switch for said motor, a pivoted tone 35 arm for said phonograph, means responsive to the operation of the phonograph for swinging said arm through a record playing range from a record beginning position to a record ending position, said tone arm being manually returnable 40 from the record ending position to the record beginning position, and means responsive to such movements of said tone arm for opening and closing said switch such that the motor is automatically stopped when a record playing operation 45 is completed and is restarted when the tone arm is manually returned to record beginning position.

12. In a phonograph, a tone arm, a vertical shaft on which said tone arm is mounted to swing in a horizontal plane from a record beginning position, through a record playing range to a record ending position and return, a ratchet wheel rotatively supported on such vertical shaft and biased to an initial rotative position, a ratchet pawl for said ratchet wheel which is rotated about the periphery of the ratchet wheel in a direction to advance said wheel with said tone arm when the latter is moving towards record ending position, a check pawl for said ratchet wheel, means biasing said pawls against said ratchet wheel, a motor for said phonograph, motor control means for starting and stopping said motor, means operated by said ratchet wheel when advanced by said pawls for operating the motor control means to stop the motor, means operated by the return movement of said tone arm to record beginning position for releasing said pawls thereby allowing the ratchet wheel to return to its initial position, and resilient means 60 for operating the motor control means to start said motor when said ratchet wheel is returned to its initial position.

13. A phonograph, an electric motor for driving said phonograph, a switch for controlling said 75

- motor, a tone arm for the phonograph mounted for rotation back and forth about a vertical axis and pivoted for movement up and down about a horizontal axis to permit of the usual freedom 5 of movement of the tone arm in the normal operation of such phonograph incident to the playing and changing of records and means responsive to both of such movements for opening and closing of said switch.
- 10 14. A phonograph, an electric motor for driving said phonograph, a switch normally biased to closed position for controlling said motor, a tone arm mounted for rotation about a vertical axis between record beginning and record ending positions and inclusive of a record playing range, 15 and mounted for rotation about a horizontal axis for movement above and below a record playing elevation, means responsive to the lowering of said tone arm below record playing elevation for opening said switch, and means responsive to movement of said tone arm to record ending position for opening said switch.
- 15 15. A phonograph including a cabinet, a horizontal record supporting turn table above the top wall of said cabinet, a hollow shaft extending through the top wall of said cabinet to one side of said turn table, a vertically movable tone arm secured to said shaft above said wall, an electric motor for driving said turn table and a control switch for said motor beneath said wall, a part hooked to the under side of said tone arm and extending downward through said hollow shaft for operating said switch in response to the vertical movements of said tone arm, and means beneath said wall operated by rotational movement of said shaft and tone arm also for operating said switch, said two switch operating means being so correlated with the movement of the tone arm as to start and stop said motor as required for the normal operation of said phonograph.
- 20 16. In a phonograph a turn table, a tone arm, a hollow vertical shaft therefor, said tone arm being secured to said shaft by a horizontal pivot which permits raising and lowering of the tone arm, an electric motor for driving said turn table, 25 a switch for controlling said motor, a post ex-
- tending between the tone arm and the vicinity of said switch through said hollow shaft for operating said switch in response to vertical movements of said tone arm, a ratchet mechanism operated by the rotary movement of said tone arm and shaft, and cam means between said ratchet mechanism and post whereby said switch means may also be operated by rotary movement of said tone arm, there being a lost motion connection between said post and tone arm whereby 30 said post may be moved by the cam means to operate the switch means without vertical movement of said tone arm.
- 25 17. In a phonograph, a record-supporting turn table, a tone arm pivoted for rotation in a horizontal plane over said turn table from an outer position to one side of said turn table, inwardly through a record-beginning position adjacent the periphery of the turn table, through a record playing range, to a record ending position near 35 the center of the turn table, said tone arm also being pivoted for movement in a vertical plane to permit its being moved above and below record-playing elevation, said tone arm having a position of rest to one side of said turn table and below record playing elevation, an electric motor for driving said turn table, an energizing circuit for said motor, circuit controlling means associated with said circuit for energizing and deenergizing the motor and for varying the voltage 40 applied thereto, and means controlled by the horizontal and vertical movements of said tone arm for operating said circuit controlling means, to deenergize the motor when the tone arm is moved to its position of rest, to energize the motor at a given voltage when the tone arm is raised above playing elevation, to energize the motor at a lower voltage when the tone arm is lowered to playing elevation at record beginning position, to maintain the motor energized at such 45 lower voltage when the tone arm is moving inwardly over the record playing range when at record playing elevation and to deenergize the motor when the tone arm reaches record ending position while at record playing elevation.

ALFRED F. WELCH.
